SKI POLE RINGS

Alexander C. H. Weiss, Chicago, Ill.

Application February 28, 1951, Serial No. 213,190

3 Claims. (Cl. 280—11.37)

(Granted under Title 35, U. S. Code (1952), sec. 266)

The invention described herein, if patented, may be manufactured and used by or for the Government for governmental purposes without the payment to me of any royalty thereon.

This invention relates to ski pole rings and especially to the mounting of such rings on the ski poles or sticks.

It is well known that ski pole rings must be flexibly mounted on the poles. This has usually been accomplished by means of crossed leather thongs or straps, which are expensive to make and attach and are unsatisfactory because of the propensity of leather to absorb moisture and then freeze hard. A number of patents in the prior art have suggested various mountings but many of these seem undesirable because they are too complicated or expensive, or use too much rubber or metal, or are too heavy, or for some other reason.

This invention aims to provide ski pole rings and attaching means which use a minimum of strategic materials, which permit a wide angle of swing of the rings, which are easy to assemble and disassemble, which make possible some adjustment of the connection, which are adequately strong, will not freeze, and may be manufactured on a large scale at a low cost.

Fig. 1 is a horizontal section on line 1—1 of Fig. 2 but on a smaller scale;

Fig. 2 is a section on line 2—2 of Fig. 1 but on a larger scale, showing the lower end only of the ski pole or stick and showing in dotted lines extreme positions which the ski pole ring may assume relative to the stick;

Fig. 3 is an exploded view in perspective of the parts which secure the ring to the stick;

Fig. 4 is a plan view of a modified form of ski stick ring;

Fig. 5 is a section on line 5—5 of Fig. 4;

Fig. 6 is a plan view of a fastening element used on the ring of Figs. 4 and 5; and

Fig. 7 is a section on line 7—7 of Fig. 6.

Referring particularly to Figs. 1, 2 and 3, the preferred form of the invention comprises a ski stick ring 10 made of plastic material as described below. Ring 10 includes a rim 11, arms 12 and a hub 13 integral with each other. Rim 11 has an annular concavity or recess 14 on the underside surface providing a circular edge 15 which may bite into the surface of the snow to prevent side slipping. Hub 13 is formed in two layers at the time the ring is made so as to grip between said layers a cup member 16, preferably of aluminum, having an integral circular flat flange 17 provided with an annular series of perforations 18 through which the plastic enters to make a bonded union, as shown in Fig. 2. Cup member 16 has a central opening 16a considerably larger than the stick and also has a cup-like recess 16b in its center for receiving two spaced clamping or compression rings 19, 20 which grip between them a rubber ring 21 of circular cross section that is designed to engage the ski stick 22 directly. Compression rings 19, 20 are of aluminum or a hard plastic, said rings having

2

opposed sloping or beveled surfaces 19a, 20a respectively to engage the rubber ring. A screw cap 23, also preferably of aluminum, with a central opening 23a for the ski stick, is screwed on the threads 24 provided on the outside of cup member 16 and engages compression ring 19 to move said ring toward compression ring 20 thereby to compress and deform the rubber ring 21 and cause it to grip the ski stick. This deformation is approximately shown in Fig. 2. If preferred, the periphery of screw cap 23 may be knurled to give a good grip so that it may be tightened or removed by hand.

The ski stick 22 is a hollow pole, preferably of aluminum or other light metal, with a pointed lower end 25 and an arcuate reduced portion 26 about five inches from the lower extremity. If the ski stick is $\frac{3}{4}$ in. in diameter, the reduced portion 26 will be about $\frac{7}{16}$ in. in diameter at its thinnest point. The rubber ring will then be about 1.125 in. in outside diameter and about 0.375 in. least inside diameter so that it must expand to twice its inside diameter when the ski stick is thrust through it for assembly, and will contract to fit on the reduced portion 26 very tightly. However, the ski stick ring is held flexibly and may pivot on the ski stick through a maximum of 30° in any one direction, or in other words, any point on the rim of the ski stick ring may move through an arc of 60° measuring from one extreme to the other, as the dotted lines of Fig. 2 indicate. This pivoting of the ski stick ring will take place most readily when the rubber ring is compressed the least, as will be readily understood; obviously, the swinging or tilting of the ring on the stick is possible because the rubber ring flexes and changes its shape. Control of the ease of movement of the ski stick ring may be had by employing rubber rings of varying softness, also by tightening the screw cap more or less. If preferred, locking means (not shown) may hold the screw cap in any screwed up position so that rough handling will not loosen the screw cap.

To assemble the ring and ski stick, the pointed lower end of the ski stick is thrust through the opening in the center of the ski stick ring and the ring is then pulled on. A little soap or other lubricant coated on the lower end of the ski stick will aid in this assembly.

The ski stick ring is preferably molded from glass fabric and a resin. One composition which has given good results was as follows:

	Percent by weight
Chopped glass fibers	55
Resin (including catalyst)	45

Another satisfactory ring was made from:

	Percent by weight
Chopped glass fibers	45
Asbestos fibers	10
Resin (including catalyst)	45

In each instance the resin could be as follows:

	Percent by weight
Paraplex P-43	89.0
Paraplex P-13	9.5
Luperco ATC	1.5
	100.0

"Paraplex" is a trade name for an alkyd resin manufactured by Resinous Products & Chemical Co., Philadelphia, Pa. "Luperco ATC" is the trade name for organic peroxides sold by the Lucidol Division, Novadell-Agene Corporation, Buffalo, N. Y., for use as catalytic or oxidizing agents.

Matched dies may be employed and a charge weighing about 0.28 lb. may be put in the mold, with a molding pressure of about 1000 p. s. i., with a temperature of

250° F., the curing time being 3 minutes. The finished ring may weigh about 4 oz. exclusive of the screw cap, the rubber ring and the two aluminum compression rings. A white pigment may be incorporated in the mix prior to the molding so that the finished ring is white enough to be scarcely noticeable against a background of snow.

In general, the resins which can be used satisfactorily to make ski pole rings are high impact type thermosetting resins having very low moisture absorption and good impact strength at -65° F. Among such resins are the class known as polyesters, of which alkyd plus styrene polymer is a good example. Some phenol-formaldehyde and melamine-formaldehyde resins are also satisfactory. In some cases, polymerization takes place exothermically while in other cases heat must be supplied. Temperatures range from room temperature to 310° F. and pressures from atmospheric to 1000 p. s. i. or more.

The described ring will not rust or corrode or rot; it has an exceptionally high strength-weight ratio; it may be manufactured by automatic machinery; its assembly is a simple operation; it requires little metal; it will not absorb water and then freeze; and finally, it is a poor conductor of heat, hence will not absorb heat from the rays of the sun (as metal rings do) and then melt snow lying thereon to cause the building up of ice layers from the frozen snow water in temperatures below the freezing point. A further advantage is the ease of assembling the ring on the ski pole: the pole need only be thrust through the center of the ring. When in position, the ring will swing as readily in one direction as in another, so that the mounting may be termed a universal joint.

In case it is desired to employ a somewhat simpler construction requiring less metal and fewer parts, the form of Figs. 4-7 may be preferred. Here the ski pole ring 39 (also of plastic as described above) has a circular rim with an annular recess 31 on its under side, and four integral arms or spokes 32 which connect the rim with a hub 33 having a central hole 34 for the ski pole. Arms 32 are of a wavy formation so as to increase the flexibility of the ring, which reduces its liability to breakage when subjected to sharp blows. A rubber ring 35 (like ring 21) is held adjacent hole 34 by a cup-like metal plate 36 which is secured by rivets 37 to hub 33. Plate 36 has a central opening 38 for the ski pole. No adjustment of the grip of the rubber ring on the ski pole is possible with this construction, nor is a 60° total swing of the ski pole ring permitted. The form of Figs. 4-7 is somewhat easier to mold as there is no problem of bonding a plastic mass to a central metallic cup member, as in the form of Figs. 1-3. If it is considered necessary to conserve metals, plate 36 may be of a hard plastic or hard rubber. Throughout this specification when "rubber" is mentioned, vulcanized natural rubber or synthetic rubbers or elastomers of various compositions are intended to be covered.

Obviously, the present invention is not limited to the particular forms herein shown and described.

What I claim is:

1. In combination, a ski pole, a ski pole ring, means flexibly and removably securing the ski pole ring to the ski pole, said means comprising a deformable rubber ring surrounding and frictionally gripping the pole, a holder fixed to the center of the ski pole ring and surrounding the rubber ring and confining it against displacement

relative to the holder, operator-actuated means forming a complementary part of said holder and adapted to be screwed onto the holder and then imparting a thrust such as will deform the rubber ring laterally to press it against the ski pole to increase said frictional grip; said holder being permanently fixed to the ski pole ring and providing a cup-like member, a pair of compression rings being within the cup-like member on either side of the rubber ring, said compression rings having opposed beveled faces contacting the rubber ring on opposite sides, and said operator-actuated means being a cap screwed on the holder and bearing against one of the compression rings to tighten it against the rubber ring.

2. In combination, a ski pole, a ski pole ring, means flexibly and removably securing the ski pole ring to the ski pole, said means comprising a deformable rubber ring surrounding and frictionally gripping the pole, a holder fixed to the center of the ski pole ring and surrounding the rubber ring and confining it against displacement relative to the holder, operator-actuated means forming a complementary part of said holder and adapted to be screwed onto the holder and then imparting a thrust such as will deform the rubber ring laterally to press it against the ski pole to increase said frictional grip; the ski pole having a generally circular cross section and being of materially reduced circular cross section at the place where the ski pole ring is mounted thereon, the portion of reduced cross section being smallest at its middle and gradually increasing in cross section in both directions longitudinally of the pole, said portion of reduced cross section having a length materially greater than the height or thickness of the rubber ring which surrounds and contacts it; said holder having internal circular openings above and below the rubber ring which openings provide relatively wide spaces surrounding the reduced portion of the ski pole, such spaces and the resilience of the rubber ring coacting to permit lateral swinging of the ski pole ring through a considerable arc relative to the ski pole without impairment of the frictional grip of the rubber ring on the ski pole and without longitudinal shifting of the ski pole ring on the ski pole.

3. The invention defined in claim 2, wherein the ski pole ring is itself a rigid assembly consisting of a rigid rim, a plurality of arms rigidly connected at their outer ends to the rim, and a hub to which the arms are rigidly connected at their inner ends; said holder including a cup member which is rigidly secured to the hub on the inside, a screw cap which is screwed on the cup member, and means surrounding the rubber ring and confined by both the cup member and the screw cap for holding the rubber ring against displacement relative to the ski pole ring; said internal circular openings being provided in both the cup member and the screw cap.
